COMBINED BRUSH HOLDER AND MIRROR ATTACHMENT FOR SUN VISORS OR SIMILAR ARTICLE

Lester R. Peilet and Irving Mark, Chicago, Ill.

Application October 25, 1955, Serial No. 38,569

Term of patent 14 years

(Cl. D14—6)

FIG. 1

FIG. 2

Figure 1 is a perspective view showing the front, top and left side of a combined brush holder, and mirror attachment for sun visors or similar article, embodying our new design;

The brush and fragmentary portion of a sun visor or similar article are disclosed by means of dotted lines in Figure 1 only for purposes of illustration.

We claim:

The ornamental design for a combined brush holder and mirror attachment for sun visors or similar article, substantially as shown and described.
